US0D1030396S

(12) **United States Design Patent** (10) **Patent No.:** **US D1,030,396 S**
(45) **Date of Patent:** **** Jun. 11, 2024**

(54) **DISPENSER**

(71) Applicant: **Arman Melkonian**, Granada Hills, CA (US)

(72) Inventor: **Arman Melkonian**, Granada Hills, CA (US)

(73) Assignee: **Brio Water Technology, Inc.**, City of Industry, CA (US)

(**) Term: **15 Years**

(21) Appl. No.: **29/862,262**

(22) Filed: **Dec. 8, 2022**

(51) **LOC (14) Cl.** **07-01**

(52) **U.S. Cl.**

USPC **D7/307**

(58) **Field of Classification Search**

(57) **CLAIM**

I claim the ornamental design for a dispenser, as shown and described.

DESCRIPTION

FIG. 1 is a top perspective view, showing my new design for a dispenser;

FIG. 2 is a bottom perspective view;

FIG. 3 is a front elevation view thereof;

FIG. 4 is a rear elevation view thereof;

FIG. 5 is a left side elevation view thereof;

FIG. 6 is a right-side view thereof;

FIG. 7 is a top plan view thereof; and,

FIG. 8 is a bottom plan view thereof.

The broken lines show portions of the dispenser that form no part of the claimed design.

1 Claim, 8 Drawing Sheets
